UNITED STATES PATENT OFFICE.

VICTOR PINGRET, OF CLEVELAND, OHIO.

ACETYLENE-GAS GENERATOR.

1,112,092.

Specification of Letters Patent Patented Sept. 29, 1914.

Application filed December 13, 1909. Serial No. 532,846.

To all whom it may concern:

Be it known that I, VICTOR PINGRET, a citizen of the Republic of Brazil, residing temporarily at Cleveland, in the county of 5 Cuyahoga and State of Ohio, have invented certain new and useful Improvements in Acetylene-Gas Generators, of which the following is a specification.

My invention relates to gas generating 10 appliances, and has particular reference to apparatus designed for the production of acetylene gas from calcium carbid.

The paramount object of the improvements which constitute the subject matter of 15 this application for patent is:—to provide an apparatus for the generation of acetylene gas under pressure, all handling of the carbid from which the gas is produced, subsequent to the placing of the material 20 within the receiving hopper, being eliminated.

Other objects of this invention are:—to provide means for the generation of acetylene gas without loss of the gas; to furnish 25 an apparatus for the purpose stated in which the admission of air to the gas will be prevented, thus insuring the delivery of a pure, unmixed product, and to produce an appliance in which the generation of gas 30 will be contiguous, this result being brought about by the special arrangement of the parts which will permit of the thorough removal of the residue from the used carbid, without interruption to the generating 35 process.

Among other important features of this invention are the automatic action of the feeding pump, which will continue to convey measured charges of carbid to the generating tank, so long as the feed hopper is 40 kept properly supplied with the gas producing material; and in addition, the fact that the chambers of the apparatus are gas tight and remain unopened during the cleaning 45 procedure, thus permitting the continuous production of gas to be carried on with perfect safety.

I accomplish the desired results by the 50 employment of the apparatus illustrated in the accompanying drawing which forms a part of this application.

Figure 1 represents a longitudinal vertical median section, some of the parts being shown in full, and Fig. 2 is an enlarged detail view of the valve operating mechanism

taken at right angles to Fig. 1 of the drawing.

Referring specifically to the construction as disclosed in the drawing, the numeral 1 indicates a cylindrical generating cylinder or tank, arranged horizontally and furnished with supports 2 resting upon a suitable foundation 3. The ends of the cylinder or tank are closed by threaded caps 4, 5. The rear cap 4 is furnished with a water gage, or indicator 6, provided with a minimum index 7, which marks the lowest level to which the water may be allowed to recede. Projecting through the side walls near the upper part of the tank are bolts 8 which support a horizontal baffle plate 9, furnished with numerous holes 10.

The front cap 5 is provided with a central aperture surrounded by an inwardly projecting collar 11. Applied to the outer face of the said cap 5, is a cylindrical valve casing 12 having a flange 13, secured to the cap by bolts or rivets 14. The chamber of the casing 12 is in alignment with the central aperture of the cap 5, and within the continuous bore thus formed, is arranged a valve plunger 15, which is adapted to be rotated axially as well as moved longitudinally in said bore. The inner end of the plunger is enlarged to form a valve head 16. The shoulder 17 formed by the enlargement engages a similarly shaped seat 18 in the end of the collar to form a gas-tight joint. The outer end of the casing 12 is closed with the exception of a central aperture for the passage of the rod 19 which is rigidly fixed to the plunger and supplied at its outer end with a hand wheel 20, and surrounding the rod, between the wheel and the casing end, is a coiled spring 21 which normally urges the valve 16 against its seat. The plunger 15 is provided with a recess 22 in one side, and when the valve is in the position shown in the drawing this recess registers with the mouth of a hopper 23 formed with the casing 12 and when the plunger is pushed inwardly its side closes the discharge end of the hopper.

Projecting vertically through the upper side of the generating tank and about midway thereof is a pipe 24, having its lower end extending below the baffle plate 9 and its upper end communicating with the interior of a pump barrel or cylinder 25, extending parallel with the said tank, and co-

extensive in length therewith. The said cylinder or barrel 25 is supported in part by the said pipe 24 and also by a second smaller pipe 26 forming a gas passage between the front end of the cylinder 1 and the pump cylinder. Upon the upper side of the said cylinder 25 and communicating with its interior is a comparatively short pipe 27, flaring above to form a feed hopper 28, fitted with a gas tight cover 29. The side of this hopper is tapped for a gas pipe 30, which leads to a suitable gas holder (not shown) placed at any convenient point.

The ends of the barrel or cylinder are closed by threaded caps 31, 32, the rear cap 31 being made much longer than the other, so that it can be screwed out or in to vary the length of the barrel bore, for a purpose that will be hereinafter explained. The front cap 32 has a threaded opening to receive the end of an outlet pipe 33, bent, as shown, to elevate the outlet above the pump, and furnished with a reduction valve 34. The bore of the barrel is divided into a front chamber 35, and a rear chamber 36, by a transverse partition 37, having a comparatively large aperture 38. Secured to the cylinder 25 and communicating with said front chamber 35 is a valve casing 75 having a spring-held safety valve 76 and the cylinder is also supplied with a pressure gage 77.

Arranged in the rear chamber 36 is a compound feed piston comprising a fore piston 39, and a rear piston 40, separated by an interval 41, and rigidly joined by a rod connection 42. Both pistons are furnished with suitable packing rings 43 to insure a gas-tight fit in the barrel, and lubricating material is supplied as required through an oil hole 44 in the cylinder wall. The connected pistons are operated by a rod 45, which is attached to the rear piston and projects through a central aperture in the cap 31. Surrounding this rod between the rear piston and the said cap is a motor spring 46, of suitable dimensions to force back the piston when the pressure within the barrel 25 has fallen to a certain predetermined point, as will be more fully explained in connection with the operation of the machine. This spring is an important element in my invention, and provision is made for the necessary adjustment of the tension to correspond with variation in the gas pressure by the aforesaid elongation of the rear cap 31, which forms the abutment for one end of said spring. To limit the backward movement of the piston, a stop 47 is inserted through the wall of the cylinder. The annular chamber 41 between the pistons is normally directly above the bore of the pipe 24 when there is no gas pressure, and constitutes a loading chamber, its capacity having a predetermined relation to the gas area of

the machine, which comprises the chamber or compartment 48 above the baffle plate, the front chamber 35 of the pump cylinder and the bore of the connecting pipe 26, all of these spaces being filled with asbestos wool 49 saturated with acetone, preferably. Extending transversely in the discharge pipe 27 of the feed hopper 28 is a rock shaft 50, carrying floats or wings 51 adapted to agitate the contents of the hopper when the shaft is rocked, to facilitate the descent of the said contents into the loading chamber 41. The said shaft 50 is operated from the piston rod 45, by means of an arm 52, fixed thereon, and connected to a rock arm 53 on a projecting end of the shaft by a rod 54. The said rod slides loosely in an eye 55 in the end of the arm 52, a yielding connection being made through the medium of a coiled spring 56, embracing the rod, and engaging a fixed collar 57 thereon and the arm 52. It will be understood that this arrangement will permit the arm 52 to travel the full extent of the piston stroke while the rock shaft arm and rod 54 are moved only a fraction of the distance.

Immediately below the pipe 24, within the tank 1, is arranged a slaking hopper 58, furnished with numerous perforations 59 in its walls, and provided internally with a series of superposed horizontally arranged wire screens 60, varying in the size of their mesh. That portion of the pipe 24 extending below the baffle plate 9 is furnished with apertures 24^a to aid the free circulation of water and arranged in the hopper immediately beneath the outlet of said pipe is a conical imperforate deflector 60^a, supported in the center of a screen 60^b consisting of a plate having the form of an inverted frustum of a cone, and provided with comparatively large apertures 60^c. The purpose of said deflector 60^a is to distribute the carbid evenly upon the screens near the sides of the hopper and thus cause the evolved gas to spread out freely beneath the baffle plate and prevent it from ascending directly into the mouth of the said pipe 24. The said hopper 58 connects at its lower end with a receiving pipe 61, projecting through an aperture in the cylinder bottom wall and extending vertically downward. This pipe 61 forms a residue chamber and has two gate valves 62, 63, arranged at the upper and lower ends of the chamber and operated by hand wheels 64. An air or vent pipe 65 connects with the receiving pipe 61 immediately below the upper valve 62, and is furnished with a vent, or air valve 66.

Just above the lower valve 63, a water pipe 67 communicates with said pipe 61, and this also has a controlling valve 68. The valves 66 and 68 are respectively furnished with sprockets 69, 70, over which passes an operating chain 71. By this de-

vice it will be seen that the connected valves must move in unison, thus preventing the turning of either without affecting the other, and the valves are relatively arranged so that they are both always in the same operative position. The sprockets 69, 70, are arranged adjacent the stems 72 of the valves 62 and 63, and upon each of the said stems is mounted a finger or pawl 73. These pawls are connected to their respective stems by hinge joints 74, which permit them to yield in one direction but render them rigid in the other. The joint of the finger corresponding with the upper valve 62 is so arranged that when this valve is opened the said finger will engage the sprocket chain and move the latter in such a direction as to close the air and water valves 66 and 68, and since the said finger yields in the opposite direction, the sprockets are not affected by the closure of the said valve 62. The action of the lower valve 63 is contrary to that just described; that is, when this valve is opened its finger will engage the sprocket chain and move it in such a direction as to open the air and water valves 66 and 68, while closing this valve 62 does not affect the sprocket chain and the valves 66 and 68 will remain open so far as the closing action of this valve is concerned. Stated more concisely, opening the upper valve 62 closes the air and water valves, while opening the valve 63 opens the air and water valves. No effect is had upon the water and air valves through the closure of the said valves 62 and 63.

The operation of my improved automatic gas generator is as follows:—The tank 1 is filled with water up to the baffle plate, and the asbestos in the space above the baffle plate as well as the pipe 26 and the chamber 36 saturated with acetone. The double piston will be held by the motor spring in its extended position, with the loading chamber 41 directly over the pipe 24. The feed hopper 28 is then filled with carbid and the cover 29 closed down tightly. The valve 62 should be open, while the corresponding valve 63 and the air and water valves 66 and 68 will be closed, thus leaving a vertical passage open from the barrel 25 through the pipe 24, the slaking hopper 58 and the residue chamber 61 to the closed valve 63. A charge of carbid is placed in the hopper 23, and the operator then seizes the stem of the plunger and pushes it into the tank until the pocket 22 is beyond the valve seat 18. He then gives the plunger a half turn by means of the hand wheel 20 so that the contents of the pocket will fall by gravity within the tank. The plunger is then permitted to return by the action of the coiled spring 21, and the pocket 22 again placed below the said hopper 23. This procedure cannot be repeated, if a sufficient quantity of carbid has been deposited in

the tank. As soon as the gas eliminated by the action of the water in the tank upon the carbid thus introduced has reached a sufficient degree of pressure the piston in the pump cylinder 25 will be moved thereby until it is arrested by the stop 47. The loading chamber 41 is thus brought directly beneath the main feed hopper 28, and a portion of the carbid therein will fall by gravity into said chamber, this action being assisted by the agitation of the wings 51. The feed piston will remain in this extended position until the pressure of the gas in front of it is reduced to a sufficient extent to allow the spring 46 to expand. This will then drive the piston forward to its initial position over the end of the pipe 24, and when the chamber 41 has reached this point its contents will fall through said pipe into the hopper 58 where it will be intercepted by the screens 60, and exposed to the slaking action of the water. When the hydrating action is completed, the residue will pass through the meshes of said screens and be deposited at the lower end of the receiving pipe 61. The gas eliminated from each fresh charge of carbid will increase the pressure in the tank 1, and force the piston of the pump back again to the loading position shown in the drawing, where it will receive another charge from the feed hopper. This procedure will be automatically continued so long as the calcium carbid is supplied to the feed hopper in sufficient quantities. The chamber 41 will be filled with gas after it dumps its load and when it returns to the feed hopper this gas will be displaced by the fresh charge of carbid and expand within the said hopper, from which it is conducted to a holder by means of the pipe 30.

It will be necessary from time to time to remove the waste material which has accumulated within the residue chamber 61. This is done without disturbing the automatic feed in the following manner:—The upper main valve 62 is first closed, shutting off communication between the receiving pipe or residue chamber and the hydrating tank, but without affecting the water and vent valves. The valve 63 is then opened, the air and water valves being at the same time automatically opened, and the chamber 61 is then emptied, cleaned and thoroughly washed out with water. When the cleansing process is completed the valve 63 is closed, and the pipe or chamber 61 will completely fill with water, since the water and vent valves are still open. When the said chamber is full of water, the upper valve 62 is opened, the act of opening automatically closing the water and air valves.

Having thus described my invention what I claim as new, is:—

1. In an acetylene gas machine, a generating tank having gas and water compart-

- ments, a feed cylinder communicating with said tank, a hopper communicating with said cylinder, a reciprocating piston mounted in said cylinder, means for conducting 5 gas from the generating tank to said cylinder, said means supplied with an absorbent material, a residue chamber communicating with the generating tank, and means in said chamber controlling the admission thereto 10 and discharge therefrom of residue received from the generating tank.
2. In an apparatus for generating acetylene gas, a generating tank, a baffle plate dividing the interior of the tank into gas 15 and water compartments, an absorbent material in the gas compartment, a feed cylinder communicating with said tank, a hopper for the cylinder, a piston in said cylinder, a loading chamber in said piston, a slaking hopper in said tank, and a residue chamber communicating with said hopper.
3. In an apparatus for generating acetylene gas, the combination of a generating tank having a water compartment and a 25 gas compartment therein separated by a screen, an absorbent arranged in said gas compartment, cylinder communicating with the gas and water compartments of said generating tank, said cylinder having a gas 30 compartment with an absorbent therein, an outlet communicating with said gas compartment, and a piston chamber, a reciprocating chambered piston arranged in said chamber, said piston adapted to be operated 35 by the gas-pressure in said cylinder, means for admitting a supply of gas generating material to said piston chamber, means within said tank for screening the generating material, and means for discharging 40 waste material from said tank.
4. In an apparatus for generating acetylene gas, the combination with a generating tank, a perforated partition in said tank, a cylinder connected with the tank, a piston 45 in said cylinder, a loading chamber in the piston, a spring adapted to project the piston, a hopper arranged to register with the said chamber when the piston is retracted, absorbent material arranged above the 50 said partition, a discharge chamber for the tank, and valves for the discharge chamber.
5. In an apparatus for generating acetylene gas, the combination of a generating
- 55 tank, a baffle plate in the tank, a discharge pipe for said tank, means for introducing an initial charge of gas producing material into the tank, a piston cylinder communicating with the tank, a chambered piston in said cylinder, and a feed hopper adapted to register with the said piston chamber when 60 the piston is at one end of its stroke.
6. In an apparatus for generating acetylene gas, the combination of a generating tank, a feed pump comprising a cylinder, a pipe connecting the cylinder and tank, a 65 perforated slaking hopper arranged within the tank beneath the said pipe, a series of screens in the hopper, and a discharge chamber communicating with said hopper.
7. In an apparatus for generating acetylene gas, the combination with a generating tank, of a feed pump comprising a cylinder, a piston in said cylinder, a loading chamber in the piston, a spring adapted to extend the piston, a hopper for the cylinder, an 75 agitator in the hopper, and operative connection between the agitator and the piston.
8. In an apparatus for the purpose specified, the combination with a generating tank, of a feed pump for the gas generating 80 material, said pump comprising a cylinder communicating with the tank, an apertured transverse partition dividing the cylinder into two compartments, an absorbent material in one of said compartments, a yielding chambered piston in the other compartment, a feed hopper, a cover for the hopper, a pipe communicating with the interior of the hopper, a rock shaft in the hopper, arms on said shaft, and operative means connecting the shaft with the said piston. 85
9. In an apparatus for generating acetylene gas, the combination of a generating tank, a feed pump, a pipe connecting the said pump with the tank, a perforated slaking hopper arranged within the tank beneath said pipe, a deflector below the outlet of the pipe, screens in the hopper and a discharge chamber communicating with the hopper. 95

In testimony whereof I affix my signature in the presence of two witnesses.
